UNITED STATES PATENT OFFICE.

EMIL SCHUCH, OF MUNICH, GERMANY.

CUSHIONING DEVICE.

1,084,491.

Specification of Letters Patent. Patented Jan. 13, 1914.

Application filed July 15, 1913. Serial No. 779,109.

To all whom it may concern:

Be it known that I, EMIL SCHUCH, a subject of the King of Bavaria, residing at 25 Giselastrasse, Munich, Bavaria, Germany, have invented certain new and useful Improvements in Cushioning Devices; and I do hereby declare the following to be a full, clear, and exact description of the invention.

The invention relates to pressure indicators or other pressure measuring apparatus employed for indicating and recording the pressure of liquids.

The object of the invention is to provide a new and improved cushioning device arranged to cushion the plunger in the pressure cylinder on the sudden application of the initial pressure, so that the indicator mechanism is not subjected to sudden dangerous shocks or jars.

In order to accomplish the desired result, use is made of a pressure cylinder having a partition dividing the cylinder into inner and outer pressure chambers filled with a liquid, and a plunger slideable in the pressure cylinder and extending through the inner chamber into the outer chamber, the plunger having means to connect one chamber with the other after initial pressure has been exerted against the entire area of the plunger and the latter has moved to connect the chambers with each other so that for a short moment the pressure is exerted against a reduced area of the plunger.

A practical embodiment of the invention is represented in the accompanying drawings forming a part of this specification, in which similar characters of reference indicate corresponding parts in all the views.

Figure 1 is a sectional side elevation of the cushioning device; Fig. 2 is an inverted sectional plan view of the same on the line 2-2 of Fig. 1; Fig. 3 is a sectional side elevation of the partition and a modified form of the plunger; and Fig. 4 is an inverted sectional plan view of the same on the line 4-4 of Fig. 3.

The pressure cylinder *a* is provided with a partition *b* in which is slidably mounted a plunger *c* pressed on by a spring *e* abutting with its outer end of a cap *f* and resting at its inner end on a collar *g* arranged on the plunger *c* so as to normally hold the plunger in the position shown in Fig. 1. The partition *b* is preferably screwed into the

lower end of the pressure cylinder *a* and is provided with a perforated sleeve *l* carrying a packing *h* to prevent leakage past the plunger *c* into the upper end of the cylinder *a* containing the spring *e*.

By reference to Fig. 1 it will be noticed that the partition *b* divides the cylinder *a* into an inner chamber *i* and an outer chamber *k*, of which the latter is closed by a cap *d* connected by a pipe or other means with a source of liquid pressure supply. The lower end of the plunger *c* is provided with channels *o*, which may be arranged exteriorly, as shown in Figs. 1 and 2, or interiorly, as indicated in Figs. 3 and 4, the upper ends of the channels terminating within the partition *b* at the time the plunger *c* is in normal position, as illustrated in Figs. 1 and 3. Both chambers *i* and *k* are filled with liquid and are disconnected from each other as long as the plunger *c* is in a normal position. The upper end *m* of the plunger *c* is connected in the usual manner with the operating mechanism of the pressure indicator or other pressure measuring apparatus employed for recording the pressure of a liquid.

The operation is as follows: When the liquid in the outer chamber *k* is subjected to pressure then an initial movement is given to the plunger *c* in an upward direction against the tension of the spring *e*, the pressure being exerted against the full area of the plunger. Immediately after the plunger *c* begins to move its channels *o* connect with the inner chamber *i* and consequently pressure is exerted by the liquid onto the liquid contained in the inner chamber *i*, and when this takes place the pressure against the plunger *c* is reduced owing to the pressure being exerted against a reduced area of the plunger *c*, that is, that portion occupied by the channels *o*. This reduction of pressure on the plunger *c* takes place in an exceedingly short period of time, and as it is not intended to reduce the pressure but only the jar or shock incident to the beginning period of pressure, it is evident that a cushioning is obtained in an exceedingly short time.

At the end of the pressure period the pressure in both chambers *i* and *k* is reduced and the spring *e* now returns the plunger *c* to its normal position. By dividing the cylinder *a* into two chambers filled with liquid it is possible to cushion the hammer action

of the applied pressure so that the indicator mechanism is not subjected to dangerous shocks or jars.

I claim as my invention:

- 5 1. A cushioning device for pressure measuring instruments, comprising a pressure cylinder and a plunger therein for operating an indicator, the pressure cylinder having a partition dividing the said cylinder into two chambers filled with a liquid and of which the outer chamber is connected with a source of pressure supply, and the said plunger is provided with channels normally terminating in the partition and adapted to connect the chambers with each other on the initial movement of the plunger. 20
- 10 10 into two chambers filled with a liquid and of which the outer chamber is connected with a source of pressure supply, the said chambers being disconnected when the plunger is in its initial position, but connected with each other by openings within the plunger immediately after the pressure is applied and the plunger has started on its initial movement. 25
- 15 15 2. A cushioning device for pressure meas- 30

uring instruments, comprising a pressure cylinder and a plunger slidable therein for operating an indicator, the pressure cylinder having a partition dividing the said cylinder into two chambers filled with a liquid and of which the outer chamber is connected with a source of pressure supply, and the said plunger is provided with channels normally terminating in the partition and adapted to connect the chambers with each other on the initial movement of the plunger. 30

In testimony whereof I have signed my name to this specification in the presence of two subscribing witnesses.

EMIL SCHUCH.
